UNITED STATES PATENT OFFICE.

ALBERT L. MILLER, OF JOHNSTOWN, PENNSYLVANIA.

AUTOMATIC SAFETY CUT-OFF.

Application filed April 30, 1923. Serial No. 635,580.

To all whom it may concern:

Be it known that I, ALBERT L. MILLER, a citizen of the United States, residing at Johnstown, in the county of Cambria and State of Pennsylvania, have invented certain new and useful Improvements in Automatic Safety Cut-Offs, of which the following is a specification.

The invention relates to a controlling valve adapted for use in a gas supply system, and particularly in the smaller pipes located adjacent a burner or other point of gas consumption. The valve which is the subject of the present invention is adapted to be automatically closed upon a reduction of pressure within the pipe in which it is located, and is delicately balanced so as to be sensitive to much smaller variations in pressure than the devices of this general character which have been in use heretofore.

An object of the invention, therefore, is to provide an improved safety valve of the character described which will automatically close upon reduction of gas pressure, and which will be automatically locked in the closed position until manually released.

A further object is to provide improved locking and lock retaining mechanism for use in connection with the valve.

Another object is to provide a substantial structure which, while sensitive to slight changes in pressure, is nevertheless capable of withstanding very large pressures.

Another object is to provide an improved form of casing for the valve mechanism.

Other objects will appear hereinafter.

The invention is illustrated in the accompanying drawings in which:—

Figure 1 is a central vertical section through the valve casing, the valve and locking mechanism being shown in elevation.

Figure 2 is a top plan view of the same.

Figure 3 is a view similar to Figure 1 showing a modification.

Figure 4 is a perspective view showing the improved lock and retaining and release mechanism therefor, these parts being the same in both embodiments of the invention.

50 The reference numeral 10 denotes a valve

casing, which is shown as comprising an upwardly and outwardly flaring portion 11 and a horizontal portion 12, the latter being provided with screw threaded end portions into which are screwed gas pipe sections 13, 14, one of which leads from a gas main, and the other to a burner or other point of use. Extending across the valve casing is a transverse partition 15 formed with a valve seat 16.

Under normal operation the gas passes freely through the valve casing from the inlet pipe 13 through the valve seat to the outlet pipe 14, as indicated by the arrows. When, however, the pressure in the pipe line is for any cause materially reduced it is desirable that the flow of gas to the burners be entirely cut off in order to avoid leakage of gas at the burner. To accomplish this result a safety valve 17 is provided which is automatically closed whenever the gas pressure falls below a certain point.

As shown the stem 18 of valve 17 works in a guide member 19 which is preferably threaded into the horizontal portion of the casing 11. This guide member is provided with a plurality of vertical gas passages 20 leading to a pressure chamber 21 within the flaring portion of the casing. A flexible diaphragm 22, which may be of leather or other suitable material, closes the upper portion of the chamber 21.

In order to protect the diaphragm 22 in case of excessive pressure a metallic guard ring 23 is provided. This ring is preferably separated from the diaphragm by means of a spacing ring 24. Above the guard ring is secured a bracket 25 which supports the automatic locking mechanism for the valve stem. Covering the whole mechanism is a dust guard or cover 26, which is shown as outwardly flanged as at 27 and bolted to a corresponding flange 28 of the casing 11 by means of bolts 29 which serve also to secure the diaphragm 22, guard ring 23, spacing ring 24 and bracket 25.

As shown the valve stem 18 is provided with an extension 30 which is screwed into the upper portion thereof and extends through the diaphragm 22. A reinforcing

plate 31 rests upon the diaphragm 22 being of sufficient size to cover the opening in the guard ring 23. The reinforcing plate is locked in position by means of a nut 32 which is threaded upon the stem extension.

Under normal conditions the mechanism is in the position shown in full lines, the valve 17 being raised by means of the gas pressure which acts through the medium of the diaphragm 22, the weight of the valve and stem being preferably counterbalanced in part by means of a weight 33 which is shown as adjustably mounted upon a stem 34 hinged to the valve stem 16 and fulcrumed within a bracket 35, which forms an extension of the stem guide 19.

When the pressure beneath the diaphragm is reduced the valve 17 is lowered to its seat 16 due to the weight of the valve and stem.

20 In order to prevent the valve from again opening upon a subsequent increase of pressure an automatic locking mechanism is provided. This locking mechanism is sensitive in its operation, and serves to positively lock 25 the valve in the lowered position until the lock is manually released.

As shown the lock consists of a weighted locking segment 38 mounted upon a shaft 39 journaled in the bracket 25. When the 30 pressure falls and the valve stem 19 is in its lowered position the segment 38 assumes the position shown in dotted lines in Figure 1, the lock being directly over the top of the stem thus preventing the valve from being 35 opened.

To return the lock to inoperative position a manually actuated releasing mechanism is provided. As shown this mechanism consists of a plate 39' having offset portions 40, 41, bent at right angles to the plane of the plate, these offsets forming ears which are suspended from the shaft 39. The portion 41 is extended to form an operating lever which is readily accessible when the 45 dust guard or cover 26 is removed. When the locking segment has been returned to the position shown in full lines in Figure 1 the valve stem will be at once returned to the raised position, provided the gas pressure within the system has been restored to 50 normal. The lower end of the plate 39' now projects below the top of the valve stem as shown in Figures 1 and 3. At the upper end of the plate is provided a forwardly extending member 42 which coacts with the upper arm 43 of a bell crank 44, pivotally mounted upon the bracket 25. The other arm 45 of the bell crank forms a catch which engages a pin 46 on the 55 locking segment 38. The weight of the plate 39' is so distributed that the plate tends to swing beyond the vertical position and the lower edge of the plate rests lightly against the top of the valve stem.

When the stem is lowered, therefore, the plate 39' swings in a counterclockwise direction, thus releasing the bell crank 44, and catch 45 whereupon the locking segment 38 falls of its own weight to the locking position.

70 Preferably a spring 46 is provided for the purpose of assisting the operation of the locking segment. As shown the spring is coiled about the ends of the shaft 39, one end of the spring bearing against a pin 47 on the locking segment 38.

The construction shown in Figure 3 is the same as that just described in connection with Figures 1 and 2 except that diaphragm 49, spacer 50, guard ring 51 and 80 bracket 52 are screw threaded within the upwardly flaring casing 53, a shoulder 54 being provided upon which the diaphragm rests.

85 It is obvious that numerous other changes may be made in the details of construction without departing from the spirit of the invention.

I claim:

1. An automatic gas cutoff mechanism 90 comprising the combination with a valve casing, valve seat and vertically reciprocating valve of a stem extending above said casing, a weighted locking segment pivoted above the valve stem, means for normally retaining said locking segment in inoperative position, said means being adapted to engage the upper portion of the valve stem in its raised position.

2. An automatic cutoff mechanism comprising in combination a pressure chamber, 100 a diaphragm located therein, a valve having its stem secured to said diaphragm and adapted for reciprocating movement, a weighted locking segment pivoted above said stem, a pivoted lock retaining member adapted to normally hold said segment in inoperative position, said retainer having a portion adapted to engage the upper end of the valve stem.

105 3. An automatic gas cutoff mechanism comprising in combination with a valve casing, valve seat and vertically reciprocating valve of a stem extending above said casing, a locking member pivoted above the valve stem, and a catch engaging the upper end of the valve stem in its raised position for retaining the lock in inoperative position.

110 4. An automatic gas cutoff mechanism 120 comprising in combination with a valve casing, valve seat and vertically reciprocating valve of a stem extending above said casing, a locking member pivoted above the valve stem, and a pivoted catch engaging the upper end of the valve stem in its raised 125 position for retaining the lock in inoperative position.

5. An automatic gas cutoff mechanism comprising in combination with a valve casting, valve seat and vertically reciprocating valve of a stem extending above said casting, a locking member pivoted above the valve stem, a pivoted catch engaging the upper end of the valve stem in its raised

position for retaining the lock in inoperative position, and a pivoted bell crank one arm of which engages a portion of said catch, while the other arm engages a pin on said locking member.

In testimony whereof I affix my signature.

ALBERT L. MILLER.
